UNITED STATES PATENT OFFICE.

MAX GOLDBERG, OF SANTA CLARA, CUBA.

ANT-TRAP FOR FURNITURE.

SPECIFICATION forming part of Letters Patent No. 694,738, dated March 4, 1902.

Application filed December 12, 1901. Serial No. 85,609. (No model.)

To all whom it may concern:

Be it known that I, MAX GOLDBERG, a citizen of the Island of Cuba, residing at Santa Clara, in the Island of Cuba, have invented 5 certain new and useful Improvements in Ant-Traps for Furniture, of which the following is a specification.

In the warm climate of Cuba it requires constant vigilance in efforts to keep ants from 10 the dining-table, and for this purpose I know that water-containing ant-traps for furniture-legs have been used. For fastening metal cup-traps for this purpose to table-legs my 15 improvement resides in the construction shown in the drawing and will be set forth in the claim appended hereto.

The drawing shows part of a table-leg cut in two parts 1 and 2 above the caster. Each cut end has its surface reduced to make the 20 abutting ends of equal diameter and with straight walls 3, so that a metal tube 4 can be fitted on these straight end walls, with the ends abutting at the cut 11 about the middle of the length of the tube. The upper part 25 of the tube has an external cup part 6, which rises above the level of the upper end of the tube for containing water to form the trap. The ends 5 of the tube abut against shoulders of the cut leg ends, which gives a firm seating. 30 for the tube and makes it both a binder-band and a brace for the joined leg parts. In applying the tube it is driven on the end of the upper leg part, and the lower leg end part is driven into the lower end of the tube, and the 35 cut end parts are then secured together, with the metal tube self-bound around the joining of the cut leg ends and forms an external lateral brace thereto.

For fastening the leg ends together at their 40 joining within the trap-tube a tubular metal core 7 is driven into a bore which passes through the lower leg end part into the upper leg part, so that this core crosses the abutting ends, forming a firm lateral brace thereto. The bore in the upper leg part is of less 45 diameter than the bore in the lower leg end part, and the core is formed with a shoulder 10 to limit the extent to which it is driven

into the upper leg part. To secure the severed ends of the leg parts together vertically, 50 a screw-bolt 8 is driven through the unthreaded bore of the metal core and engages the upper leg part, the head 9 of the bolt engaging the lower end of the metal core, and thereby firmly draws and holds the severed leg end 55 parts together. In this bolting action the core-shoulder 10 serves as an abutment to hold the core against the inward force of the bolt in drawing the leg ends together. An advantage of this core-and-bolt fastening is 60 that the head of the bolt is utilized to form a supporting-seat for the upper end of the caster-stem, and thereby keeps the bolt from working loose in moving the table.

In drawing the leg ends together the bolt 65 serves also to draw the shoulders of the leg ends upon the ends 5 of the trap-tube, so that the severed leg parts when joined upon the trap are very thoroughly braced externally by the metal trap and internally by the metal 70 core and bolt, making a very effective means for applying a metal water-containing cup to table-legs, the object being to provide a fastening device for a metal ant attachment to table-legs which are cut in two parts to receive such attachment above the caster. 75

I claim—

A table-leg attachment for ant-traps consisting of severed leg parts, a tubular metal cup-trap receiving and laterally bracing the 80 cut leg ends in abutting relation, a tubular metal core centrally connecting and laterally bracing the cut ends and a bolt passing through the core, connecting the core and the 85 table ends, the tubular core, the bolt and the trap-tube crossing the joining of the cut table ends and bound together in the way shown and described.

In testimony whereof I affix my signature in presence of two witnesses.
